UNITED STATES PATENT OFFICE

DANIEL F. LEPLEY, OF CONNELLSVILLE, PENNSYLVANIA.

SAFETY ATTACHMENT FOR ELEVATORS.

1,260,216.

Specification of Letters Patent. Patented Mar. 19, 1918.

Application filed September 19, 1917. Serial No. 192,163.

To all whom it may concern:

Be it known that I, DANIEL F. LEPLEY, a citizen of the United States, residing at Connellsville, in the county of Fayette and 5 State of Pennsylvania, have invented a new and useful Safety Attachment for Elevators, of which the following is a specification.

This invention relates to safety devices for elevators, and while it is capable of being used in connection with all kinds of passenger and freight elevators, it is primarily 10 designed for use in connection with elevators of that type used in mines. The invention is designed primarily as an improvement upon the construction disclosed 15 in my Patent No. 826586, issued to me on July 24, 1906.

In devices such as herein made and as shown, for example, in my patent herein 20 mentioned, it has been difficult to remove and replace the wedges employed and which wedges must be renewed when the teeth thereof become worn off to an objectionable extent.

25 Prior devices have also been objectionable because they have necessitated, as in my patented structure, the use of steel castings for holding the wedges. Such castings have always been difficult to obtain in 30 regular quantities and under present conditions are not only almost unobtainable, but are very expensive.

One of the objects of the present invention is to so mount the wedges of the safety 35 device that they can be quickly and completely removed and others substituted without necessitating practically the dismantlement of the cage, as heretofore, and which wedges do not require the use of extensive 40 castings to hold them in position.

A further object is to simplify and lighten the safety device without reducing its efficiency, but on the contrary making it more reliable in action and capable of more ready 45 installation.

A still further object is to provide a safety device combined with a structure made up of standard materials which can be easily procured and assembled.

50 A still further object is to provide equalizing means whereby should one of the shaft guides become worn to a greater extent than the other, the wedges would nevertheless

bind with equal pressure upon the respective guides, thereby equalizing the grip at 55 both sides of the cage to equally support said sides and prevent sagging.

Another object is to provide, in connection with the safety wedges, means for preventing extensive vibration at the top of the 60 cage when running at a high speed, thus insuring proper contact of the safety wedges with the guides, when an emergency arises.

Another object is to combine with the equalizing mechanism a means whereby the 65 safety mechanism will not be wrecked and the cage permitted to drop should the bridle chains that connect the hoisting cable with the cage fail or break.

With the foregoing and other objects in 70 view which will appear as the description proceeds, the invention resides in the combination and arrangement of parts and in the details of construction hereinafter described and claimed, it being understood 75 that changes in the precise embodiment of the invention herein disclosed, can be made within the scope of what is claimed, without departing from the spirit of the invention.

80 In the accompanying drawings the preferred form of the invention has been shown.

In said drawings:—

Figure 1 is an elevation of the upper 85 portion of a cage and showing the present improvements combined therewith.

Fig. 2 is a side view of the structure shown in Fig. 1.

Fig. 3 is an enlarged side elevation of one 90 of the safety clutches.

Fig. 4 is a front view of the structure shown in Fig. 3.

Fig. 5 is a section on line 5—5 Fig. 3.

Referring to the figures by characters of 95 reference, 1 designates a portion of a cage structure having combined therewith a tiltable platform structure only the upper portion of which has been shown in the drawings, said upper portion being indicated at 100

2. The tiltable structure is adapted to be locked against swinging movement relative to the cage structure 1, but as the locking means constitutes no part of the present invention, it has been deemed unnecessary to 105 show or describe it. The cage 1 is designed

to travel upon guides G extending downwardly within the shaft of the elevator, and the sides of the cage are so shaped as to straddle these guides and work freely upon them, said sides having outstanding parallel flanges provided for this purpose and as shown at 3. Arranged above the sides of the cage are upper and lower plates 4 and 4' and these plates connect parallel angle beams 5 which are extended vertically and are attached to the cage structure. From the plate 4 project outwardly extending angle strips 6 which are parallel and constitute supplemental means for slidably 10 engaging the guides G, thereby to prevent the upper portion of the cage from vibrating to an objectionable extent while the cage 6 is moving at a high speed. This insures the proper application of the safety 15 clutches as will be hereinafter more fully described.

Secured to the angle beams 5 close to the top of the cage are links 7 from which extend upwardly converging chains 8 which 20 are attached to a sleeve 9 clamped upon the hoisting cable C. The lower end of the hoisting cable is provided with a socket S attached in the usual manner to a main lifting equalizer 10 having bridle chain 11 25 diverging downwardly therefrom and attached to the side portions of the cage. A V-shaped breakable link 12 is supported by the lifting equalizer 10 and is attached to the intermediate portions of parallel levers 30 13 of supplemental equalizing means, there being a rod 14 pivotally attached to these levers 13 midway between the lower ends of the link 12 and extending downwardly through a coiled spring 15 which exerts a 35 constant downward pull upon the rod.

Brackets 16 are mounted on the cage near the sides thereof and fulcrumed on each of these brackets is a lever 17 the inner end of which is connected to the adjacent ends 40 of the levers 13 by a link 18. The outer ends of the lever 17 are connected to the wedges forming the safety clutch members of the present invention, and which will be hereinafter described. It is to be understood 45 that four of the levers 17 are used, two being located adjacent each side of the cage to form a pair and the levers of each pair being connected by links 18 to the levers 13 as before pointed out.

Secured to and extending outwardly from each of two lower plates 4' are angle strips 19 of a standard size, and which are so placed as to converge upwardly, as shown 50 particularly in Fig. 3. The outstanding flange of each of these angle strips is provided with a longitudinal slot 20 and secured along the outer face of each flange parallel with and close to the slot 20 is a holding strip 21. Slidably mounted on the 55 inner faces of the flanges of strips 19 are

wedges 22, the inner faces of which are substantially parallel and provided with teeth 23 while the opposed faces of the wedges fits snugly against the inclined flanges of the strips 19. These wedges can be readily 70 forged from standard billets and each of them is held to its angle strip 19 by a bolt 24. The bolt is screwed into the wedge and works freely in the slot 20. The head 24 of the bolt is angular and is held against 75 rotation by the holding strip 21. Thus it will be seen that the bolt cannot become accidentally unscrewed from its wedge 22 and will nevertheless be free to slide upwardly and downwardly within the slot 20 during 80 the corresponding movement of the wedge 22 relative to the angle strip 19.

Stems 25 extend upwardly from the wedges and are provided with laterally extending studs 26 to which are connected 85 the outer ends of the levers 17.

It is to be understood that the guides G are positioned between the wedges 22 and under normal conditions the cage will move upwardly and downwardly upon the guides 90 without the wedges coming into contact with said guides. However, should the hoisting cable C break, the spring 15 would promptly pull downwardly through rod 14 upon the equalizing levers 13 and cause 95 said levers to transmit motion through links 18 and levers 17 to the wedges 22. These wedges are normally in their lowermost positions with the bolts 23 close to the lower ends of the slots 20. However, when the 100 wedges are shifted in the manner pointed out they will move upwardly along the inclined flanges of the angle strips 19 and, consequently move toward each other, thus to cause the teeth 23 to bite into opposed 105 faces of the guides G and prevent the cage from dropping. Should one of the guides wear to a greater extent than any other, the equalizing connections between the wedges will insure the wedges firmly gripping the 110 guides irrespective of the variation in the thicknesses of said guides.

Should the bridle chains 11 which connect the cable socket S to the cage give way, the breaking of the connection 12 would prevent the entire weight of the cage from being placed on the wedge mechanism and possibly wrecking it. This is due to the fact that the link 12 is just strong enough to hold spring 15 normally under full compression, 120 but in case of a bridle chain failure, this link will break before the load will wreck the other mechanism.

Should the wedges become worn, thus 125 making it desirable to replace them with new ones, the repairs can be made without the expenditure of the time and trouble heretofore necessary. The strips 21 are first unfastened from the angle strips 19. The cotter pins 27 or other fastening means em- 130

ployed for holding the studs 26 in engagement with the lever 17 are removed and the levers 17 disengaged from the studs. By then unscrewing the bolts 23 the wedges 5 can be lifted out from engagement with the angle strips 19 and new ones easily substituted.

It will be apparent that a safety device such as described can be much more cheaply 10 made and repaired than can those devices requiring the use of special castings or the use of parts which so interfit that it becomes a difficult matter to take them apart. By using standard sizes of material which can 15 be purchased in the open market and assembling them as described, the structure is not only cheapened in cost and simplified in construction, but is rendered more durable and more efficient in operation.

20 What is claimed is:—

1. A safety device for elevator cages, including opposed angle members converging upwardly, wedges interposed between and slidably upon the angle members, said 25 wedges being insertible laterally in position between the members, there being a longitudinal slot in each of said members, a fastening device slidably mounted in each slot for holding a wedge against displacement relative to the slotted member, and means for 30 slidable engagement by the fastening device to hold said device against detachment from the wedge and its slotted member.

2. In a safety device for elevator cages, 35 opposed upwardly converging angle members having longitudinal slots, opposed wedges interposed between said members and slidably engaging them, said wedges being removable laterally from between the members, fastening means slidably mounted within the slots and threaded into the respective 40 wedges, and means detachably secured to the slotted members for holding the fastening means against unscrewing during the relative 45 movement of the wedges and slotted members while the cages are in operation and in the event of an emergency.

3. The combination with guides, and an elevator cage mounted between the guides, of 50 upwardly converging angle members at the sides of the cage and arranged in pairs, each guide being extended between the members of one pair, all of the members being slotted longitudinally, opposed wedges at opposite 55 sides of each guide and between the slotted members of each pair, fastening means slidably mounted in the slots and threaded into the respective wedges, means on the slotted members for holding the fastening means 60 against rotation during their movement with the wedges relative to the slotted members, hoisting means, connection between said hoisting means and the wedges for holding the wedges normally apart and out of contact with the guides, and means for auto-

matically shifting the wedges upwardly along the slotted members and into engagement with the guides when relieved from the pull of the hoisting means.

4. The combination with guides, and an 70 elevator cage, of upwardly converging angle members arranged in pairs, each guide being extended between the angle members of each pair and said members being slotted longitudinally, wedges interposed between the 75 members of each pair and insertible laterally between said members and the guide adjacent thereto, fastening means engaging the wedges and slidable in the slots, means for holding the fastening means against detachment during their movement with the wedges, a hoisting cable, a hoist equalizer connected thereto, connections between said equalizer and the cage, a supplemental equalizing lever, a breakable connection between 80 said lever and the hoist equalizer, yielding means for exerting a downward pull upon the supplemental lever, levers connected to the wedges, and connections between said levers and the supplemental equalizing lever. 85

5. The combination with guides, of an elevator cage slidably mounted thereon, outstanding means upon the sides of the cage for straddling and slidably engaging the guides, supplemental means connected to and 90 supported above the cage for engaging and straddling the guides, outstanding upwardly converging angle members at the sides of the cage and interposed between said upper and lower guide engaging means, wedges 100 interposed between the angle members and the guides and insertible and removable laterally relative thereto, a spring, a spring restraining lever on the cage, hoisting means for holding the lever against the action of 105 its spring, and operative connections between the lever and the respective wedges, said lever and connections constituting an equalizer shiftable under the action of the spring when released from the hoisting means to 110 shift the wedges relative to the angle members and bind upon the guides.

6. The combination with guides, and an elevator cage, of guide gripping members including wedges, a hoisting cable, a hoist 115 equalizer connected thereto, connections between said equalizer and the cage, a supplemental equalizing lever, a breakable connection between said lever and the hoist equalizer, yielding means for exerting a downward pull upon the supplemental lever, levers connected to the wedges, and connections between said levers and the supplemental equalizing lever. 120

7. The combination with a guide and an 125 elevator cage slidably mounted on the guide, of upwardly converging angle members secured to the cage and extending to opposed sides of the guide, opposed wedges insertible laterally between the guide and the respec- 130

tive members, a slidable connection between the wedges and said members, each of said connections including a bolt threaded into the wedge and slidable within the adjacent member, and means fixed to the member and close to the bolt for holding said bolt against rotation relative to the wedge.

In testimony that I claim the foregoing as my own, I have hereto affixed my signature in the presence of two witnesses.

DANIEL F. LEPLEY.
